Primary Examiner — Justin M Jonaitis*Assistant Examiner* — Jennifer S. Yosinski(57) **CLAIM**

The ornamental design for a hanger, as shown and described.

DESCRIPTION

FIG. 1 is a perspective view of a hanger of the present invention.

FIG. 2 is a front view of FIG. 1.

FIG. 3 is a rear view of FIG. 1.

FIG. 4 is a right side view of FIG. 1.

FIG. 5 is a left side view of FIG. 1.

FIG. 6 is a top view of FIG. 1; and,

FIG. 7 is a bottom view of FIG. 1.

The broken lines depict portions of the hanger that form no part of the claimed design.
